UNITED STATES PATENT OFFICE.

JOSEPH W. JONES, OF CORNING, NEW YORK, ASSIGNOR TO INGERSOLL-RAND COMPANY, OF JERSEY CITY, NEW JERSEY, A CORPORATION OF NEW JERSEY.

PLATE VALVE.

Application filed October 5, 1922. Serial No. 592,487.

To all whom it may concern:

Be it known that I, JOSEPH W. JONES, a citizen of the United States, and a resident of Corning, in the county of Steuben, State 5 of New York, have invented a certain Plate Valve, of which the following is a specification, accompanied by drawings.

This invention relates to plate valves, but more particularly to a plate valve of the 10 type in which a circular valve plate lifts between the valve seat and a stop plate and is returned to its seat by means of suitable springs.

The objects of the invention are to improve 15 upon the construction of such valves, especially valves of relatively small diameter intended for the smaller sizes of pumps and compressors and obtain a simple and cheap valve having all the advantages of 20 adequate port area and maximum lift found in larger valves, but without complicated or expensive parts.

Other objects of the invention are to reduce 25 the clearance required in the pump or compressor due to the valves thus producing higher volumetric efficiency, and produce a small valve of the type described having the minimum amount of spring tension so that small power is required for operating, 30 which is a particularly important factor in vacuum pumps, for instance.

Further objects of the invention will hereinafter appear and to all of these ends the invention consists of a valve having the features 35 of construction, combinations of elements and arrangement of parts having the general mode of operation substantially as hereinafter described and claimed in this specification, and shown in the accompanying drawings, in which

Figure 1 is a transverse sectional view of the complete valve with the parts assembled.

Figure 2 is a detail view showing the valve seat in transverse vertical section,

Figure 3 is a perspective view of the valve plate,

Figure 4 is a perspective view of one of the valve springs,

Figure 5 is a perspective view of another 50 valve spring,

Figure 6 is a perspective view of the two valve springs assembled and one superimposed upon the other,

Figure 7 is a transverse sectional view of 55 the stop plate, and

Figure 8 is a horizontal sectional view of Figure 7 taken on the line 8-8 looking in the direction of the arrows.

Referring to the drawings, the valve seat A of the valve, is provided with the required ports B over which the circular valve plate C is adapted to be seated in the usual manner. A bolt D having a head E and a nut F is provided for holding the parts of the valve together.

A stop plate G, in this instance held against the valve seat A by means of the bolt D, is provided with a portion H extending over the plate valve C, which lifts from its seat and is adapted to be returned by means of springs J and K interposed between the valve plate C and the stop plate G.

The springs J and K in this instance are formed as a pair and have substantially the same diameter as the valve plate C. The springs are preferably formed out of flat sheet metal, having greater width than thickness and one spring is superimposed upon the other between the valve plate and the stop plate.

Two springs of the type described have been found to operate satisfactorily and well, although the invention is not limited to two springs and more could be used, if desired. The springs J and K are oppositely coiled, that is one forms a right hand coil and the other forms a left hand coil, and each spring preferably consists of one convolution through an arc of substantially 360°. In placing the springs one upon the other and arranging the two between the valve plate and the stop plate, the open ends a-b and c-d are located substantially diametrically opposite each other, and the open ends of one spring lie over solid portions of the other spring as indicated in detail in Figure 6.

In accordance with the construction shown and with the springs formed and arranged as described, light spring tension is obtained, but of sufficient strength to cause the valve to operate efficiently and without spring breakage. The tension in the spring is substantially uniformly distributed and the deformation of the springs may occur as rapidly as required for the operation of the valve without placing undue strain upon any particular portion or portions of the springs. The two springs together form

a unitary construction and yet each spring is separate and independent and forms an element of the unit.

I claim:

5. 1. A plate valve comprising a valve seat, a circular valve plate, a stop plate extending over the valve plate, and a pair of oppositely coiled springs, having substantially the diameter of the valve plate superimposed one on the other and arranged between the valve plate and stop plate.

10 2. A plate valve comprising a valve seat, a circular valve plate, a stop plate extending over the valve plate, and a pair of oppositely coiled springs formed of flat sheet metal having greater width than thickness, said springs being of substantially the same diameter as the valve plate and being superimposed one on the other and arranged between the valve plate and the stop plate.

15 3. A plate valve comprising a valve seat, a circular valve plate, a stop plate extending over the valve plate, and a pair of oppositely coiled springs formed of flat sheet metal having greater width than thickness, and each having one convolution, said springs being of substantially the same diameter as the valve plate and being superimposed one on the other and arranged between the valve

20 30 plate and stop plate.

4. A plate valve comprising a valve seat, a circular valve plate, a stop plate extending over the valve plate, and a pair of oppositely coiled springs formed of flat sheet metal having greater width than thickness, and each having one convolution, said springs

being of substantially the same diameter as the valve plate and being superimposed one on the other and arranged between the valve plate and stop plate with the open 40 side of the convolution constituting each spring over said solid portion of the other spring.

5. A plate valve comprising a valve seat, a circular valve plate, a stop plate extending 45 over the valve plate, and a pair of oppositely coiled springs formed of flat sheet metal having greater width than thickness and each having one convolution, said spring being of substantially the same diameter as 50 the valve plate and being superimposed one on the other and arranged between the valve plate and stop plate with the open ends of the convolution constituting each spring located substantially diametrically opposite 55 each other and over solid portions of the other spring.

6. A plate valve comprising a valve seat, a circular valve plate, a stop plate extending over the valve plate, and a pair of oppositely 60 coiled springs formed of flat sheet metal having greater width than thickness, said springs being of substantially the same diameter as the valve plate and being superimposed one on the other and arranged between the valve plate and the stop plate with the open ends of the springs located substantially diametrically opposite each other.

In testimony whereof I have signed this 70 specification.

JOSEPH W. JONES.
